Patented Apr. 20, 1926.

UNITED STATES PATENT OFFICE.

WILLIAM OTIS WILSON, OF CLOVER, SOUTH CAROLINA.

STOP-MOTION MECHANISM FOR WINDING MACHINES.

Application filed November 24, 1924. Serial No. 752,013.

To all whom it may concern:

Be it known that I, WILLIAM O. WILSON, a citizen of the United States, residing at Clover, in the county of York and State of South Carolina, have invented certain new and useful Improvements in a Stop-Motion Mechanism for Winding Machines, of which the following is a specification.

This invention relates to improvements in stop motion mechanism for yarn winding machines.

The primary object of this invention is the provision of a stop motion mechanism for yarn winding machines, by means of which the size of the cop or ball of yarn wound may be accurately regulated.

A further object of this invention is the provision of a stop motion mechanism for yarn winding machines, by means of which the diameter of the yarn cop may be regulated, to prevent cutting of the thread by friction, when the cop has reached a predetermined size.

A further object of this invention is the provision of improved stop motion mechanism for regulating the size of yarn windings, by means of which windings of various sizes may be obtained, and by means of which the cop may be accurately regulated as to predetermined size, saving considerable quantities of yarn, which is apt to be destroyed by reason of cutting of the threads after the cop has reached a predetermined size.

A further object of this invention is the provision of an attachment which may be used on conventional types of winding machines, for accurately regulating the maximum size of the yarn winding, and which will automatically stop the winding of the yarn after it has reached a predetermined size.

Other objects and advantages of this invention will be apparent during the course of the following detailed description.

In the accompanying drawings, forming a part of this specification, and wherein similar reference characters designate corresponding parts throughout the several views,

Figure 1 is a side elevation, partly in section, showing conventional details of a yarn winding machine, such as the Foster doubling winder, with the improved attachment embodied thereon for regulating the size of the yarn cop.

Figure 2 is a view similar to that illus-

trated in Figure 1, showing the stop motion mechanism in operated relation, after the yarn cop has reached its maximum size.

Figure 3 is a front elevation, showing fragmentary parts of a conventional winding machine, with the improved attachment embodied thereon.

Figure 4 is a sectional view, showing improved details of the attachment as used upon conventional parts of a winding machine.

Figure 5 is a sectional view showing parts of the improved attachment, this view being taken substantially on the line 5—5 of Figure 4.

In the drawings, wherein for the purpose of illustration is shown only a preferred embodiment of the invention, the letter A may generally designate conventional features of any approved type of winding machine, with which the improved attachment B is to be used for regulating the size of the cop.

Referring to the machine A, the same is preferably of the type illustrated and described in Patent #1,018,920, granted February 27, 1912, to J. O. McKean. In this machine, a cam shaft 10 is provided having a cam 11 supported thereby. The frame of the machine includes standards 12 upwardly of which guide rods 13 are provided which slidably support a thread guide 14, which has a conventional lug 15 extending into the cam groove of the cam 11. At the lower ends of the standards 12, bearings are provided for rotatably receiving pins or shafts 18 and 19 therein, substantially as is illustrated in Figure 4 of the drawings. The shafts 18 and 19 are in axial alignment, and at the ends of the same which project inwardly from the bearings 17, the same support a yoke socket 20 so that the yoke socket 20 may be rocked with respect to the standards 12, in accordance with conventional winding machine construction, as will be well understood by those skilled in the art to which this invention relates. The yoke socket 20 upwardly is provided with an arm 21, upon which a laterally extending spindle 22 is provided adapted to receive the cop shell or spool onto which the thread is to be wound.

A spring 24 serves to hold the cop on the spindle 22 yieldingly against a cop driving roll 25, which is of the conventional construction.

A member 26, known to the trade as the

starting handle, is provided, which has depending spaced and aligning ears 27 bearing on the pin or shaft extensions 18 and 19, and integral with said ears 27 is an upwardly plate-like arm 28, which normally at its upper end lies rearwardly of a shifter 29. The starting handle 26 also includes a forwardly extending arm 31 having a laterally projecting lug 32 thereon which is adapted to normally rest upon a latch 33 pivoted at 34 to a stationary bracket 35. On the latch 33 is provided a plate portion beneath which and forwardly of the pivot 34 is pivotally mounted one or more drops 36, each provided with an eye 37, arms 38, and tail 39. The ends of the yarn that are being wound on the cop extend through the eyes 37 upwardly across a cross bar 40, and thence downwardly through a suitable 20 thread guide to the cop on the spindle 22. The operation of the winding mechanism thus far described will be well understood by anyone skilled in the art to which this invention relates, and if any of the threads 25 being wound should break, its drop 36 falls until stopped by the tail 39 engaging the latch 33, which brings the arm 38 of the drop into the path of a vibrating arm 42 which is fixed to a shaft 43, as in conventional construction. On its next upward stroke the arm 42 will strike the arm 38, and thereby swing the latch 33 on its pivot 34 out from beneath the lug 32, whereupon a spring 44 30 will actuate the starting handle structure 26 on the axis provided by the shaft or pin extensions 18 and 19, so as to swing the shifter 29 upwardly and against the periphery of the cop being formed, and which action will move the cop supporting arm 21 forwardly, incident to the pivotal connection of the yoke socket on the shaft extensions 18 and 19, and move the cop out of engaging relation with the winding drum 25, as can be readily understood. 35 The stop motion above described will only automatically operate because of the breaking of a thread. It will not operate when the spool or cop has reached a predetermined size, so that it is a common occurrence for the cop, after reaching a predetermined size, to have such great friction with the driving drum 25 that the threads on the cop are broken, and become tangled, causing a considerable loss of yarn. To this end, 40 the attachment B has been provided, which will cause the stop mechanism above described to automatically operate when the cop is of a predetermined size or diameter, and cause the cop support to move away from yarn engaging relation with the same. 45 The attachment B above mentioned includes the shaft or pin extension 18 above mentioned, and contemplates the provision of a set or clamping screw or member 50, 55 which is screw threaded in the yoke socket

20, as is illustrated in Figure 4 of the drawings, to insure a movement of the pin 18 with the yoke socket, as the same is moved. To this end, it can readily be understood that the pin 18 bears in the bearing 17, 70 to insure its movement with the yoke socket 20. One end of the pin or extension 18 extends inwardly from the yoke socket 20 and the adjacent ear 27 of the starting handle 26, and this end of the pin or shaft member 18 is embodied with a diametrical passageway, adapted to adjustably receive a trip lever arm 52 therein. The trip lever arm 52 is of L-shaped formation, including the body 53, an end of which extends into 80 the passageway of the shaft 18 above mentioned, and the arm 52 also includes a laterally extending end portion 54, at right angles to the body 53. A screw or clamp 55 is adjustably carried axially of the shaft 85 or pin 18, for clamping against the body portion 53 of the trip arm 52, whereby to clamp the trip arm 52 in a predetermined relation.

A post 60 is also provided as a part of the attachment B, which has a screw threaded end 61 and a lock nut 62; the end of the post 60 opposite the screw threaded end 61 being tapered or conical shaped, as at 64. This post 60 is adapted for screw threaded connection in a suitable screw threaded opening provided in the rear end of the plate portion of the latch arm 33 above described, and so that the laterally extending hook portion 54 of the trip arm 52 may engage the 100 same, as will now be described.

Referring to the operation of the improved attachment to automatically trip the top when it has reached a predetermined size, it can readily be understood from the foregoing description, that as the size of the cop increases the yoke socket 20 will be moved forwardly, by reason of its pivotal movement with the pin or shaft extensions 18 and 19 as an axis. Due to the fact that the pin 18 is connected with the yoke socket 20 by reason of the set screw 50, said pin 18 will likewise move with the yoke socket, and will swing the trip arm 52 therewith, so that as the cop increases in diameter, the end 54 of the arm 52 will move toward the post 60. The end portion 54 of the arm 52 will first engage the conical pointed head 64 of the post 60, and moving downwardly thereover will swing the latch 33 above mentioned, out of its holding relation with the lug 32 of the starting handle structure 26, releasing the same and permitting the spring 44 to actuate, in the manner above described, the starting handle, so that the brake 29 will move to engage the cop and move the same out of winding relation with the drum 25.

By reason of the provision of the shaft or pin 18 carrying the trip arm 52, cops of various diameters may be wound, since by 130

releasing the set screw 50 the shaft or pin extension 18 may be set as desired, so that the head or end 54 of the trip arm 52 will engage the post 60 at a predetermined time, 5 when the cop has reached its maximum diameter desired. The tapered head of the post 60 is important, since thereby the trip arm 52 is permitted to pass downwardly along the post when the winder tender pulls 10 the spindle or arbor 22 forward to change the cop for an empty tube. With this attachment it is impossible to start the full tube and wind more yarn on the same, after the attachment has tripped the stop mechanism as above described.

From the foregoing description of this invention it is apparent that a novel type of stop motion mechanism has been provided, which will operate to automatically 20 control the operation of winding apparatus, so that cops or balls of yarn of predetermined size, quantity, and diameter may be obtained.

Various changes in the shape, size, and arrangement of parts may be made to the form of winding machine and attachment herein shown and described, without departing from the spirit of the invention or the scope of the claims.

30 I claim:

1. In a winding machine the combination of a pivoted cop supporting member, a pivoted brake member adapted to act with a brake action on a cop being formed, 35 means including a latch to releasably hold the brake member out of breaking relation to the cop, and means carried by said cop supporting member and latch whereby to trip the latter when the cop has reached a predetermined size.

2. In a device of the class described the combination of a pivotally mounted cop supporting device, a pivotally mounted braking member cooperating with the cop support 45 device, a stop motion mechanism including a latch to releasably hold the braking member out of braking relation with the cop supporting device, a member connected with the cop supporting device and movable therewith 50 to trip the latch when a predetermined size of cop has been formed, and means for adjusting said member with respect to said cop supporting device whereby cops of various sizes may be obtained.

55 3. In a device of the class described the combination of a pivotally mounted yoke socket, a cop supporting member fixed with the yoke socket for movement therewith, a driving member, spring means normally 60 urging the cop supporting member and yoke socket so that the cop will engage said driving member to wind the yarn on the cop, a braking mechanism, a starting handle pivotally mounted in connection with said 65 braking mechanism, stop motion mechanism

including a latch to releasably hold the starting lever in position with the braking mechanism out of operation upon the cop supporting member, an arm carried for movement with the yoke socket and cop supporting member, and a post carried by said latch against which said arm will cooperate when the cop has formed to a predetermined size whereby to trip the latch.

4. In a yarn winding machine of the class 75 described the combination of a supporting frame, a yoke socket, shaft means pivotally supporting the yoke socket on the frame, means for keying said shaft for movement with said yoke socket, a stop motion mechanism including a latch, an arm carried by said shaft, and a post carried by said latch for engagement by said arm when the yoke socket has moved to a predetermined position 80 whereby to trip the latch.

5. In a yarn winding machine of the class 85 described the combination of a supporting frame, a yoke socket and cop supporting member, shaft means pivotally mounting the yoke socket and cop supporting member with respect to said frame, a starting handle 90 pivotally carried by said frame, means operated by said starting handle to move the cop and cop supporting member and yoke socket, stop motion mechanism including a 95 latch to releasably hold the starting lever inoperative with respect to the last mentioned means, and a trip arm carried for movement with said shaft and yoke socket whereby to trip the latch when the cop has formed to a predetermined size.

6. In a yarn winding machine of the class 100 described the combination of a frame, a yoke socket, a starting handle, shaft means pivotally connecting the yoke socket and starting handle on said frame, means for adjustably keying the shaft in a predetermined position with said yoke socket, an arm connected to said shaft extending laterally therefrom, a 105 stop motion mechanism including a latch for releasably holding the starting handle in a desired position, and a post carried by said latch cooperating with said arm whereby to trip the latch when the arm has moved to engage said post.

7. In a yarn winding machine of the class 110 described the combination of a supporting frame, a cop supporting mechanism, a shaft bearing in said frame for pivotally mounting the cop supporting mechanism thereon, means for moving said cop supporting 115 mechanism to a nonwinding position, stop means for said first mentioned means including a latch to releasably hold said first mentioned means out of operative relation with respect to the cop supporting mechanism, an arm laterally extending from said shaft, and means for keying the shaft to cop supporting mechanism whereby it may be fixed 120 at a desired distance with respect to said latch

so that when the cop has been formed to a predetermined size said arm incident to movement of the cop supporting mechanism and shaft will move to engage said latch for releasing the same.

8. In a yarn winding machine of the class described a supporting frame, a yoke socket, a starting handle, a shaft pivotally mounting the yoke socket and starting handle on the frame, a stop motion mechanism including a latch cooperating with said starting handle, an L-shaped trip member carried by said shaft, a post carried by said latch including a conical shaped head, and means for keying said shaft for movement with said yoke socket whereby upon a predetermined movement of the yoke socket an end of said trip member will move to engage the conical head of said post for tripping the latch.

9. In a yarn winding machine the combination of drive means, a movable cop supporting frame, means to actuate the frame into yarn winding relation with the drive means, stop means to hold the frame out of yarn winding relation with the drive means, a latch to releasably hold the stop means against its tendency and to permit the frame to lie in cop winding relation to the drive means, and trip means operative by the size of the yarn cop to release said latch with respect to the stop means.

10. In a yarn winding machine the combination of drive means, a movable cop supporting frame, means to actuate the frame into yarn winding relation with the drive means, stop means to hold the frame out of yarn winding relation with the drive means, a latch to releasably hold the stop means against its tendency and to permit the frame to lie in cop winding relation to the drive means, and adjustable trip mechanism oper-

ated by a predetermined size of the yarn cop being wound to release said latch with respect to the stop means, said trip mechanism being adjustable to permit different sizes of cops to be wound at the time of release of said latch.

11. In a yarn winding machine the combination of drive means, a spindle adapted to have a cop wound thereon, means movably supporting the spindle for movement towards or away from the drive means to control cop winding of yarn, spring means actuating on the last mentioned means to hold the spindle in cop winding relation with the drive means, spring means tending to act on the cop and means which supports the cop spindle to hold the same out of cop winding relation with respect to the drive means, latch means releasably holding the last mentioned means in position to permit winding of the cop, and means movable with the means which supports the cop spindle as the size of the cop being formed increases to trip said latch.

12. In a yarn winding machine of the class described the combination of drive means, frame means for having a cop wound thereon, means movably supporting said frame means for movement towards and away with respect to the drive means, means to hold the frame means out of yarn winding relation with the drive means, a latch device to hold the last mentioned means out of such operating relation on the frame means, an adjustable arm connected for movement with said frame means, and a post carried by the latch means having a conical end facing said adjustable arm for engagement by the arm as the frame means is moved incident to increase of the size of a cop being wound thereon.

WILLIAM OTIS WILSON.
